MANUAL CONTROLS FOR MOTOR-OPERATED WRINGERS

Irving Naxon, Chicago, Ill.

Application August 19, 1952, Serial No. 305,202

1 Claim. (Cl. 68—253)

My invention relates to wringers carried by washing machines, and more particularly to means for controlling the operation of the wringer rolls. Motor-operated wringers present a safety hazard in respect to the hand which feeds the clothes into the wringer, and conventional controls—such as a lever or switch arm—are provided in front or at the top of the wringer for actuation to stop the wringer when its use is not desired or in an emergency. However, when a finger or hand is caught in a wringer, a brief interval may occur before the other hand is applied to the stopping lever, due to pain and concentration of the victim's mind on the side of the injury, allowing more of the hand to be drawn into the wringer and increasing the injury.

In view of the above risk, it is the primary object of the present invention to provide a control which requires the constant application and pressure of the hand to induce or maintain the operation of the wringer and causes the wringer to stop the moment the pressure of the hand is relaxed or the hand removed.

Another object is to design the novel control for simultaneously procuring dual functions, one being to operate an electric motor which turns one of the wringer rolls and the other to apply pressure to the companion wringer roll in the direction of the motor-operated roll.

A still further object is to provide a wringer in which the pressure roll is applied to the motor-operated roll only by manual effort.

An additional object is to construct the motor-operated roll in a unit with the motor and the gearing which transmits the motor drive to the roll, whereby to save room and eliminate complications.

An important object is to construct the novel control in the form of a very simple mechanism which is incorporated compactly in the housing of the wringer and easily accessible for attention or repair.

With the above objects in view, a better understanding of the invention may be had by reference to the accompanying drawing, in which—

Fig. 1 is a front elevation, partly in section, showing the improved control;

Fig. 2 is an enlarged elevation from the left-hand side of Fig. 1, partly broken away;

Fig. 3 is a view showing the assembly of the lower wringer roll lowered from the wringer housing; and

Fig. 4 is a section on the line 4—4 of Fig. 3.

In accordance with the foregoing, specific reference to the drawing indicates the washing machine at 10 and the housing of the wringer mounted on the same at 11. The housing is of conventional external form; and it contains the wringer rolls 14 and 15 in the usual superimposed relation. In the present instance, the rolls 14 and 15 have their shafts journaled in bearings 16 and 17, respectively; and the housing 11 is extended at one end with a compartment 20 to accommodate an electric motor 21 which drives the roll 15. The motor shaft 22 enters a reduction-drive gear-train (which comprises a clockwork-like train of gears supported between two spaced

5 rectangular plates 23) from one side; and the shaft 24 of the roll 15 extends from the other side of the gear-train, being journaled in the corresponding plate 23. The motor, gear-train and roll 15 thus form a direct-coupled unit. In other words, the motor and gear-box are carried by and therefore float with the roll 15. The gear-train structure is rectangular in form, as is the compartment 20, so that the gear-train and motor will not rotate despite the turning influence of the roll 15. The motor is attached to the adjacent plate of the gear-train structure by rivets 23b. Four corner strut-posts 23a secure the plates 23 together, like a clockwork. The bearings 16 and 17 are separated from the gear train structure 23 by a pair of wings 11a extended inwardly from the corresponding upright of the housing 11.

10 The upper roll 14 is floatingly disposed over the roll 15, as the facing ends of the journals 16 and 17 are open as shown at 18 in Fig. 2; and down-pressure on the bearings 16 is required in order to accomplish the wringing action. Such down-pressure is preferably transmitted by a cross-bar 25 which spans both bearings 16.

15 As shown more clearly in Fig. 2, the conductors 30 and 31 leading from the motor circuit and comprising motor terminals are attached separately, as indicated at 32 and 33, to an insulation block 35 mounted over the motor. The connections 32 and 33 serve as binding posts and extend on the opposite side of the insulation block 35 with a pair of spring blades 37 and 38 which are in spaced superimposed relation.

20 The wringer housing 11 receives a control arm 40 in front having a shaft 41 which is journaled in the housing. The shaft extends with a crank 42 on the inside which is adapted to bear on the cross-bar 25 when the arm 40 is swung downwardly from the position shown in Fig. 1, so that this motion of the arm is employed to apply down-pressure to the wringer roll 14. The crank 42 is also adapted to bear down on a rod 45 attached with one end to the housing, as indicated at 45a, and extending alongside the bar 25 and out of the housing through an opening 46 in the same to a position over the motor terminal blade 37.

25 When the terminal blades 37 and 38 are separated at their free ends, as shown in Fig. 2, the motor circuit is broken and the motor is therefore idle. However, when the frontal arm 40, which is formed with a terminal handle 50, is depressed as previously stated, the rod 45 serves to bear down on the terminal blade 37 with the effect of engaging the same with the companion blade 38. This action serves to set the motor in motion, the wringer roll 15 in rotation, and the wringer roll 14 in working engagement with the roll 15.

30 It will be apparent from the above description that the operation of the wringer can be instituted only by the manual down-pressure of the control arm 40, and that such action will continue only as long as the manual pressure on the arm 40 is maintained. Ordinarily, the right hand is used for this purpose, while the left hand inserts the clothes between the wringer rolls. However, in case a finger or other part of the hand tends to become caught between the rolls, the attendant need only release the control arm 40. In such event, the pressure on the floating roll 14 will be removed immediately, so that no injury to the finger or hand will occur. Also, the release of the control arm will automatically break the motor circuit, whereby to stop the roll 15, so that the chances of injury by the continued operation of the wringer are eliminated. Besides, the blades 37 and 38 are of spring material and tend to raise the rod 45 the moment hand pressure on the control arm 40 is released, so that the control arm is automatically influenced to rise in such event.

35 It may now be assumed that the novel control imparts a high factor of safety to the wringer. First, it requires the

grasp of the control arm at all times when the wringer is in operation, so that the hand does not have to reach for any emergency control in the event that an accident in the feeding zone of the wringer rolls develops. Further, since the manual pressure on the control arm 40 is necessary for the application of the wringer roll pressure, it follows that in case of a mishap the natural tendency is to withdraw or raise the control arm. Further, it is apparent that only manual pressure can operate the upper roll 14, indicating that no other force is present at any time to require the concern of the attendant when the release of the wringer is necessary. Further, such release does not require any application of effort or work by the attendant, as the mere release of the control arm 40 relaxes the pressure of the upper wringer roll and cuts off the motor. A control mechanism is thus provided which is entirely actuated by manual application or pressure and released at will by the removal of such application, rendering the wringer safe at all times. Further, the direct coupling of the motor and gear-train to the shaft of the wringer roll 15 departs from the remote wringer drives in conventional washing machines, which occupy much room and involve bearings, numerous parts and precision in alignment, whereas the direct coupling of the motor, gear-train and wringer roll in the present invention produces a unit which is rigid, compact and quite simple.

I claim:

In a wringer, a housing of inverted U-form and receiving a pair of horizontal superposed wringer rolls and comprising an upper roll and a lower roll between its sides, the upper roll supported by and freely movable relative to the lower one, an electric motor connected to

operate the lower roll, a normally open switch for the motor, a manually operable upwardly and downwardly swingable overhead control arm carried by and rising obliquely from a journal in the housing top and effective on a manual downswing to press and maintain the upper roll against the motor-operated lower roll, and means operated by the control arm upon downward swinging thereof to close the motor switch, the motor having terminals and said switch comprising a pair of normally vertically spaced blades leading to the motor terminals, the upper blade thereof adapted to be pressed into contact with the lower blade, said means comprising a rod connected with one end to the housing and extending with the other end over the upper blade, and a crank extended from the control arm in the region of the journal and opposite said rod, the downswing of the control arm operating by way of said crank to bear on the rod and cause the same to press the upper blade into contact with the lower one.
